Specification for Design.

Patented May 17, 1921.

Application filed October 4, 1920. Serial No. 414,683. Term of patent 14 years.

To all whom it may concern:

Be it known that I, LULU V. LAVELL, a citizen of the United States, residing at Minneapolis, in the county of Hennepin and State of Minnesota, have invented a new, original, and ornamental Design for Candle-Holders, of which the following is a specification, reference being had to the accompanying drawing, forming part thereof.

The figure is a perspective view of a candle holder, showing my new design.

I claim:

The ornamental design for a candle holder, as shown.

In testimony whereof I hereunto affix my signature.

LULU V. LAVELL.
